WILLIAM SEYBOLD, OF MCKEESPORT, PENNSYLVANIA, ASSIGNOR
TO HIMSELF AND SAMUEL H. HOFFMAN, OF SAME PLACE.

Letters Patent No. 90,963, dated June 8, 1869.

IMPROVEMENT IN MINERS' LAMPS.

The Schedule referred to in these Letters Patent and making part of the same.

To all whom it may concern:

Be it known that I, WILLIAM SEYBOLD, of McKeesport, in the county of Allegheny, and State of Pennsylvania, have invented a new and useful Improvement in Miners' Lamp; and I do hereby declare the following to be a full, clear, and exact description thereof, reference being had to the accompanying drawing, making a part of this specification, in which—

Figure 1 is a side elevation of my improved miners' lamp, and

Figure 2 is a vertical section of the same.

Like letters of reference indicate like parts in each.

The ordinary miners' lamp consists of a small can, with a wick-tube fastened near its bottom, and extending upward to the level of the top of the lamp. The lamp is fastened to the miner's cap by a hook in the can. In this lamp, lard, or other expensive oils are used. The use of light, cheap oils, such as petroleum, fluid, &c., in this lamp, is attended with dangerous results, for the oil in the lamp, being constantly agitated by the movements of the miner, works its way out around the edge of the lid, and through the wick-tube, dripping from the latter, when the miner's head is bent down, in small flaming drops. In this way the outer surface of the lamp becomes wet with oil, which frequently takes fire, and sometimes the lamp explodes.

This danger and inconvenience is wholly obviated by my improvement, the nature of which consists in the construction of a miners' lamp having a wick-tube extending from the place where it is attached or fastened to the can, or body of the lamp, up through the interior, to near the top of the lamp, and the outer end of the wick-tube extended above the level of the lid of the lamp, for the purpose of burning, without danger of explosion or accident from leakage, the light oils now in use.

To enable others skilled in the art to make and use my invention, I will proceed to describe its construction and manner of use.

In the drawing—

a is the body, or chamber of the lamp, and
b is the wick-tube, which is curved where it enters the chamber of the lamp *a*, at any convenient point near the bottom, and extends upwards, both externally and internally, the external portion *b* being carried up above the level of the top of the lamp, and the inner portion, *b'*, reaching nearly to the cover, or lid *c*.

On the outer extremity of the wick-tube *b* is a sleeve, *d*.

e is the hook by which the lamp is fastened to the miner's cap.

f is cotton, or other light fibrous material in the inside of the can *a*.

g is the feeding-wick.

h is the burning-wick.

I elongate the inner end *b'* of the wick-tube *b*, and

extend it upwards inside the can *a* to near the top, and extend the outer end of the wick-tube *b* above the level of the lid *c*, to prevent the escape of the oil through the wick-tube *b*, and, by placing enough cotton, or other light fibrous material, in the can *a* to absorb the oil, I effectually stop all leakage through the wick-tube *b* and around the edge of the lid *c*.

The filling *f* of cotton, or other fibrous material, absorbs the oil or burning-fluid, and prevents its spilling out, but does not obstruct its passage through the feeding-wick *g* to the burning-wick *h*, as the filling lies closely in contact with that portion of the feeding-wick *g* which extends down from the top of the inner portion *b'* of the wick-tube to the bottom of the lamp.

Another advantage is, that the wick never requires to be changed, for the cap *d* serves as a cup, in which is placed a small wad of cotton, or burning-wick *h*, which extends down the wick-tube *b* to the wick *g*, which is drawn down the wick-tube a little way, and when the wad or burning-wick *h* has become calcined, or burned, it is taken out and replaced by a fresh one.

The lid *c* is hinged to the can *a*, on the side next to the outer end *d* of the wick-tube *b*, so that when it is opened, it interposes as a shield between the burning-wick *h* and the open end of the can *a*.

The advantage of this is, that the lamp can be filled, when burning, with perfect safety.

As by this lamp the petroleum and other light oils can be used, a very great saving is effected to the miner. It burns with perfect safety in whatever position it is placed, as well in an inverted as in an upright position.

The lamp may be made of tin or any other suitable material.

I do not wish to confine myself to the particular size and shape shown, but desire to cover all sizes and shapes to which my improvement can be applied.

Having thus described my improvement, What I claim as my invention, and desire to secure by Letters Patent, is—

1. Extending the wick-tube upwards, within the lamp-chamber, nearly to the top of the lamp, in the manner and for the purpose described.

2. In combination with the interior upward extension of the wick-tube, extending the exterior portion of the wick-tube above the top of the lamp.

3. The short burning-wick *h*, inserted into the end of the wick-tube, in combination with the feeding-wick *g* and fibrous filling *f*, substantially as and for the purposes hereinbefore described.

In testimony whereof, I, the said WILLIAM SEYBOLD, have hereunto set my hand.

W. SEYBOLD.
